UNITED STATES PATENT OFFICE.

EDWARD ERMOLD, OF NEW YORK, N. Y.

TREADLE-ACTION.

SPECIFICATION forming part of Letters Patent No. 427,227, dated May 6, 1890.

Application filed September 12, 1889. Serial No. 323,701. (No model.)

To all whom it may concern:

Be it known that I, EDWARD ERMOLD, of the city, county, and State of New York, a citizen of the United States, have invented 5 certain new and useful Improvements in Treadle-Actions, of which the following is a specification.

This invention relates to a combined treadle and clutch-operating device which is to be 10 used for lifting an object and operating a clutching device at the same time, which mechanism can be used on various kinds of machines, but is specially adapted for a corking machine for which I have filed an application, Serial No. 309,298, May 1, 1889.

The invention consists in the construction and combination of parts and details, as will be fully described hereinafter, and finally pointed out in the claims.

20 In the accompanying drawings, Figure 1 is a side view of my improved treadle and clutch-operating device applied on a bottle-corking machine, parts being broken out and others in section. Fig. 2 is a similar view of the 25 frame of the machine and treadle, the parts being in different positions and parts being broken out and others in section. Fig. 3 is a plan view of the parts shown in Fig. 2. Fig. 30 4 is an end view of the arm carrying the sliding bolt, which bolt is shown in section; and Fig. 5 is a side view of the same.

Similar letters of reference indicate corresponding parts.

From the frame A of the machine the 35 bracket A' projects, which is provided with an eye A², in which the sleeve B is mounted and guided to reciprocate vertically, in which sleeve the rod B³ is mounted adjustably, said rod being provided on its upper end with a 40 platform B⁵, for supporting the bottle in which the cork is to be inserted. The lower end of the reciprocating sleeve B is connected by a link C with a foot-lever C', pivoted on the lower end of an arm C², projecting downward 45 from the front end of the bracket A.

On the sleeve B a tappet D is fixed, and the rod B³ can be locked at any desired elevation in the sleeve B by a screw D'. On said tappet D the friction-roller e rests, which 50 is mounted on one end of an arm E, fixed on a shaft F, mounted in the lower part of the

frame A. Said shaft F is also provided with an arm G, on one side of which lugs G' are provided, between which a bar H is mounted to slide, one end of said bar being provided 55 with a top bevel H'. Suitable clips J are bolted or screwed on the lugs G' for the purpose of holding the sliding bar between the lugs. A spiral or other spring K has one end secured to a pin K', projecting from the sliding bar H, and the other secured to a pin K², projecting from the arm G, which spring K serves to pull the sliding bolt H in the direction toward its beveled end.

On the sliding bar H a lever L is pivoted, 65 which is provided at its upper end with an anti-friction roller L' and has its lower end rounded, said rounded end resting against a shoulder N, formed on a lug O, projecting laterally from the short arm P, that projects 70 downward from the arm G. A spring Q is secured to the pin K² of the arm G and to the frame A. The vertical reciprocating rod R, which actuates the clutch, is provided near its lower end with a shoulder or offset S, on which 75 the bolt H can act, and a short distance above the same a beveled toe T projects from a sleeve T', formed on an arm T², projecting from its frame A.

The operation is as follows: The wheel d, 80 which is driven by the belt g, is rotated at all times; but the shaft driven by said wheel must only be coupled with the mechanism of the corking-machine when a bottle ready to be corked is placed on the platform B⁵—that 85 is to say, when a bottle is placed on the platform B⁵ and said platform is raised, the corking mechanism must be operated only sufficiently to cork this bottle, and must then be thrown out of gear at once, even when the 90 foot-lever is depressed. By depressing the foot-lever C' the rod B³, platform B⁵, and the bottle on said platform are raised and the bottle is brought into proper position for corking. At the same time the free end of the 95 arm E is raised and the arm G swung down, as is also the sliding bolt H, which, acting on the shoulder or offset S of the clutch-rod R, pulls said clutch-rod downward, whereby the clutching mechanism is released and the shaft driven by the pulley d is engaged with the working mechanism of the corking-machine, 100

and the cork is forced into the bottle on the raised platform B. As the arm G swings downward and moves downward the bolt H, the roller L' slides down the beveled toe T, whereby the upper end of the lever L is moved in the direction of the arrow x'. The lower end of the lever L abuts against the shoulder N of the lug N', and thereby the bolt H is moved in the direction of the arrow x'. As soon as the bolt H is disengaged from the offset S, the spring W pulls the clutch-rod R upward, and the mechanism of the corking-machine is at once disengaged from the driving mechanism. The bottle still remains in raised position, but the corking mechanism is not operated. When the foot is removed from the foot-lever, the bottle-support descends and the arm G, bolt H, and lever L are brought back into the position shown in Fig. 1.

Having thus described my invention, I claim as new and desire to secure by Letters Patent—

1. The combination, with a vertically-movable clutch-operating rod and a vertically-movable platform or support, of a foot-lever for raising the platform or support, and mechanism operated by the vertically-movable support and serving to actuate the clutch-rod, substantially as set forth.
2. The combination, with a vertically-movable clutch-operating rod and a vertically-movable platform or support, of a lever for raising the platform or support, a lever actuated by said platform or support, and a sliding bolt connected with said lever, which slid-

ing bolt acts on the clutch-operating rod, substantially as set forth.

3. The combination, with a vertically-movable clutch-operating rod and a vertically-movable platform or support, of a lever for raising the support, a lever actuated by the support, a sliding bolt on said lever, a lever pivoted to the sliding bolt, a fixed beveled toe on which one end of the lever pivoted to the sliding bolt rests, and an abutment on the lever operated by the support, against which abutment that end of the toe-lever rests that is opposite the one resting on the toe, substantially as set forth.

4. The combination, with a vertically-movable clutch-operating rod and a vertically-movable support, of a lever for raising the support, a lever actuated by said support, which lever is provided with an abutment, a sliding bolt on said lever, a toe-lever pivoted to the sliding bolt, a spring for pulling said bolt toward the clutch-operating rod, a fixed beveled toe on which the roller on the upper end of the toe-lever pivoted to the sliding bolt can rest, and an adjustable tappet connected with said support, substantially as set forth.

In testimony that I claim the foregoing as my invention I have signed my name in presence of two subscribing witnesses.

EDWARD ERMOLD.
